CLAIM

The ornamental design for a display panel or screen or portion thereof with animated graphical user interface, as shown and described.

DESCRIPTION

FIG. 1 is a front view of a first embodiment of a display panel or screen with a first image of an animated graphical user interface showing our new design; and

FIG. 2 is a second image thereof;

FIG. 3 is a front view of a second embodiment of a display panel or screen with a first image of an animated graphical user interface showing our new design; and;

FIG. 4 is a second image thereof;

FIG. 5 is a front view of a third embodiment of a display panel or screen with a first image of an animated graphical user interface showing our new design; and;

FIG. 6 is a second image thereof;

FIG. 7 is a front view of a fourth embodiment of a display panel or screen with a first image of an animated graphical user interface showing our new design; and,

FIG. 8 is an eighth image thereof.

The appearance of the image may transition from one image to another image as shown in FIGS. 1-2, FIGS. 3-4, FIGS. 5-6 and FIGS. 7-8, respectively.

The process or period in which an image transitions to another forms no part of the claimed design.

The broken lines shown in the drawings represent portions of the display panel or screen or portion thereof with animated graphical user interface or an icon that form no part of the claimed design.
